UNITED STATES PATENT OFFICE.

WILLIAM F. DEWEY, OF KANSAS CITY, MISSOURI.

HEATER.

1,288,392.

Specification of Letters Patent. Patented Dec. 17, 1918.

Application filed January 24, 1916. Serial No. 73,844.

To all whom it may concern:

Be it known that I, WILLIAM F. DEWEY, a citizen of the United States, residing at Kansas City, in the county of Jackson and State of Missouri, have invented certain new and useful Improvements in Heaters, of which the following is a full and exact specification.

This invention relates to improvements in heaters, and more particularly to heaters of the gas type, the principal object of the invention being to devise an improved construction of heater for efficient generation of heat as well as providing for proper radiation thereof in the most effective manner. The invention also aims to increase the safety and the convenience of such heaters and to improve their construction generally.

To this end the invention includes, among other improvements a heater construction comprising a heating drum provided with a separable burner stand having a grating removably mounted thereon; the legs of the burner stand carry a removable heat deflector a suitable distance below the drum, and the air mixing openings of the burner are located above this deflector and at a safe distance from the hose connecting point outside the burner stand. The other features of improvement and advantage will appear in the course of the description.

With the above general object in view, the invention will now be described with reference to the accompanying drawing illustrating one form of embodiment thereof, after which those features of improvement deemed to be novel will be severally set forth and defined in the appended claims.

In the drawing—
Figure 1 is a central vertical section through a heater embodying the present improvements, said section being along the line I—I of Fig. 3;

Fig. 2 is a side elevation of the same with the drum and burner stand in separated relation and the cap member inverted; and

Fig. 3 is a horizontal section on the line III—III of Fig. 1.

Referring to the drawing in detail, a burner 2 is carried by a burner stand comprising a ring top portion 4 supported by three legs 6, secured to said ring by means

of the bolts 8. One of said legs 6 is formed with an intermediate thickened portion 10 suitably bored for receiving a valve casing 12, to which is joined a hose connection 14 and the pipe connection 16 into which is detachably fitted the lower end of the burner pipe 18 having the air mixing openings 20 adjacent its lower end. The valve casing 12 is provided with the exterior valve 22 and pilot lighter 24 swivelly mounted and adapted to throw a jet flame across the space between it and the burner 2 and below the ring 4. A downward radiation deflector 26 plate 26 is removably mounted upon lugs 28 formed upon the several legs 6 at some distance below the ring member 4, said plate 26 being formed with a central opening 30 for accommodating the burner pipe 18.

A grating 32, forming a "hot plate", is removably mounted on the top of the burner stand as thus constructed, said grating being formed with a bottom annular rib 33 adapted to fit snugly within the top margin 75 of said ring member 4.

A heater drum 34, provided with the top covering 36 but having no bottom, is arranged for removable mounting of the same upon the above described burner stand, said drum being of a diameter adapting it to fit snugly over the top portion of said stand and be supported upon the shoulders 38 formed on the outer faces of the legs 6. Suitable windows 40, of mica or the like, are 85 provided in the sides of the drum at the points illustrated, and inside the drum adjacent its upper end is secured—by means of bracket pieces 42—a second deflector member of inverted cone shape for laterally 90 diverting the upward radiation of heat. A vent outlet is provided through a top vent member 46 mounted in an opening formed centrally in said top covering 36. Associated with this vent member 46 is a skeleton 95 cap piece 48 of basket shape, having the internal annular shoulder 50 and the annular series of exterior shoulders 52. This cap piece is thus adapted to be mounted normally in the position illustrated in Fig. 1 100 with its outer margin inclosing the top edge of the vent member 46 and the latter engaging the shoulder 50; or, in inverted position as illustrated in Fig. 2, with the top

edge of the vent member 46 engaging the shoulders 52 and the cap piece forming a receptacle for receiving a cup or other object to be heated therein.

5 The above described arrangement affords a simple and effective construction for carrying out the desired objects of the improvements. With the drum mounted removably on the burner stand, the parts may be assembled as in Fig. 1, simply for heating purposes, or the drum may be removed as shown in Fig. 2, and the remaining parts be used as a "hot plate" for cooking or the like. Or, the drum may be left in place and the 10 cap piece 48 inverted for supporting a vessel or for receiving a cup or other object to be heated, where the heat thus afforded would be sufficient. When used as a heater in the form illustrated in Fig. 1, the open space 15 at the base of the drum between it and the deflector plate 26 provides for the necessary freedom of air currents so essential to proper burner action, while the deflector plate 26 intercepts the downward radiation of heat 20 from the burner and diverts to the surrounding air that percentage of such radiation which would otherwise be absorbed by the floor or other support of the stand. When desired, as for storing, cleaning or other 25 purpose, the deflector plate may be removed by simply detaching the pipe 18 and lifting out the plate 26, tilting it slightly in lifting it off the lugs 28. The burner is lighted by 30 means of a jet of flame from the pilot lighter 35 24. The pilot lighter 24 being swivelly mounted, as hereinbefore set forth, when it is desired to light the burner the pilot lighter is turned upwardly and as the gas flowing therethrough is ignited the flame is shot 40 through the space between the bottom of the drum and the deflector plate 26 in the direction of the burner. As a factor of safety, it 45 will be noted that the hose connection 14 is located outside the burner stand and below the plane of the deflector plate 26, while the air mixing openings 20 are located at the base of the burner pipe 18 within the stand and at the center thereof and above the plane of the deflector plate 26, thus guarding 50 as much as possible against the shooting back of the flame from the burner to the hose connection, a danger so common with burners of the gas type and often resulting in serious trouble and damage, caused by 55 burning away the end of the hose or so burning it as to render the joint defective. The grating 32 is readily replaceable in case it requires renewal, and it may or may not be used when the drum 34 is in place, but the 60 proportion of the parts is such that it is convenient to leave the grating assembled in the position illustrated so that it is ready for use on simply removing the drum from the stand.

65 While the foregoing represents what is

now deemed to constitute the preferred form of embodiment of the invention, the right is reserved to such formal changes or modifications as may fairly fall within the scope of the appended claims.

70

What I claim is:

1. A heater comprising a tripod burner stand, a downward radiation deflector removably supported upon the legs of said stand and provided with a central opening, 75 a pipe connection carried by one of the legs of said stand and extending wholly beneath said deflector, and a burner located within said stand and provided with a burner pipe extending through said opening and fitting removably in said pipe connection, said burner pipe having air-mixing openings located above said deflector.

2. A heater comprising a bottomless drum having a top vent opening, a burner stand 85 of skeleton form for permitting free upward passage of air through the entire bottom opening of the drum, a downward radiation deflector plate carried by said stand at some distance below the lower end of the drum, a 90 burner located within the lower portion of said drum and provided with air-mixing openings above the plane of said deflector plate, and supply-pipe members leading from said burner to the exterior of said 95 stand and provided with a hose connection positioned outside said stand and below the plane of said deflector plate.

3. A heater comprising a bottomless drum having a top vent opening, a burner stand 100 of skeleton form for permitting free upward passage of air through the entire bottom opening of the drum while supporting the latter, a downward radiation deflector plate carried by said stand at some distance below the lower end of the drum, a burner located within the lower portion of said drum, 105 supply-pipe members leading from said burner to the exterior of said stand and provided with a hose connection positioned outside the stand and below the plane of said deflector plate, and a pilot gas burner swivelly mounted adjacent said hose connection and adapted to be turned upward and project 110 a lighting flame through the space between said plate and the lower end of said drum.

4. A heater comprising a bottomless drum provided with a top vent opening, a removable stand having its upper portion shaped to telescope snugly within the lower end of 115 the drum and provided with a burner projecting within said lower end of the drum, and a grating removably mounted upon said upper portion of said stand and fitting within the lower end of said drum.

5. A heater comprising a burner stand and drum supported thereby, said drum having a top vent member and a skeleton basket-shaped cap member reversibly mounted upon said vent member for either inclos- 130

ing the latter or depending therein in receptacle form for supporting an object to be heated.

6. A heater comprising a bottomless drum 5 having a top vent opening, a removable stand having its upper portion shaped to telescope snugly within the lower end of the drum and provided with exterior shoulders for engagement with the lower margin of

said drum and removably supporting the 10 latter, a burner carried by said stand and projecting within the lower end of said drum, and a grating removably mounted upon said upper portion of said stand and inclosed by the lower end portion of said 15 drum.

WILLIAM F. DEWEY.
